United States Patent Office

Des. 213,730
Patented Apr. 1, 1969

213,730

WRAPPING PAPER OR SIMILAR ARTICLE

Nathan Shapira, 555/308 Westwood Plaza,
Los Angeles, Calif. 90024

Filed Aug. 9, 1967, Ser. No. 9,391

Term of patent 14 years

Int. Cl. D5—03
U.S. Cl. D59—2

The single figure of the drawing is a plan view of a wrapping paper showing my new design. The dash lines at the sides indicate the unit and the unit repeat.

I claim:

The ornamental design for a wrapping paper or similar article, as shown and described.
